UNITED STATES PATENT OFFICE.

JOSEPH COHN, OF NEW YORK, N. Y.

DESIGN FOR A BRACELET.

47,746.

Specification for Design. Patented Aug. 24, 1915.

Application filed March 8, 1915. Serial No. 12,969. Term of patent 3½ years.

To all whom it may concern:

Be it known that I, JOSEPH COHN, a citizen of the United States, and a resident of the city of New York, borough of Manhattan, in the county and State of New York, United States of America, have invented a new, original, and ornamental Design for Bracelets, of which the following is a specification, reference being had to the accompanying drawing, forming part thereof.

Figure 1 is an edge view of a bracelet embodying my new design; Fig. 2 is a front elevation thereof; and Fig. 3 is a fragmentary sectional view on the line 3—3 of Fig. 2.

I claim—

The ornamental design for a bracelet, as shown.

JOSEPH COHN.
